G. OSANNI

SPIRAL PULL JACK

Filed Feb. 14, 1927

Inventor
Gabriello Osanni
by his Attorneys
Baldwin Wright.

UNITED STATES PATENT OFFICE.

GABRIELLO OSANNI, OF CHESHIRE, MASSACHUSETTS.

SPIRAL PULL JACK.

Application filed February 14, 1927. Serial No. 168,101.

This invention relates to a jack particularly designed for the purpose of removing drills, rods, pipes or the like which may have become lodged or fastened in the well so that it is necessary to exert a considerable force either with or without a twisting motion for the purpose of removing the same. The invention covers a simple and efficient construction which may be used to remove either a rod or a hollow pipe by either a direct lifting movement or a lifting movement combined with a twisting movement. Detailed objects of the invention will be apparent from the following detailed description and the appended claims.

In the drawings:

Figure 1 is a perspective view of the device in operative position for removing a drill.

Figure 2 is a top plan view of the same with the drill in section.

Figure 3 is a vertical sectional view through the jack.

The device comprises a base member 1 which is preferably of frusto-conical form and is provided at one side with a handle 2 and at the opposite side with a hole 3 through which may be passed a rod 4 by means of which the base may be held against turning movement if necessary. The base is hollow and at its upper end has an internal cylindrical portion which is screw threaded as indicated at 5. With these screw threads engage external screw threads 6 on a hollow screw member 7 which is provided with a head 8 of larger diameter. The lower end of the screw 7 is provided with an external flange 9 formed by a washer which is removably fastened to the screw 7 in any desired manner. This is designed to contact with shoulders 10 on the inside of the base and limit the upward movement of the screw.

Located between the upper end of the base 1 and the head 8 of the screw 7 is a bushing or washer 11 provided with a plurality of lugs 12 which fit into corresponding openings in the top of the base 1 and prevent rotary movement of the bushing. The inside of this bushing is screw threaded to engage the screw thread 6. The screw threads in the base may be omitted.

A chuck member 13 having corrugations on its inner face is mounted in the head 8 and held in position by a rod 14 passing through the head and said chuck member. The corrugated portion of the chuck member pro-

jects slightly into the central opening of the screw. A cooperating chuck member 15 is slidably mounted in the opposite side of the head 8 and has similar corrugations on its inner face. A U-shaped yoke member 16 has both legs passing through the head 8 and engaged at their outer ends by nuts 17. An adjusting screw 18 is screw threaded through the yoke and bears at its inner end against the chuck member 15. In this manner the chuck member may be positioned as desired at first by adjustment of the yoke 16 through the screw 17 and finally by means of the adjusting screw 18.

The head 8 is provided at its sides with ears 19 which have openings therethrough to receive a rod 20 by means of which the head may be turned. A loose collar 21 overlies the head 8 and is held in position by a bead 22 on the upper end of the screw 7 which may be conveniently formed by pressing outwardly the metal to engage a slight flange on the lower part of the collar. Ball bearings 23 may be interposed between the collar 21 and the head in order to permit free relative movement between these two parts.

If it is desired to use the jack to remove a drill A or similar tool, the jack is passed over the upper end of the drill until the base rests upon the ground or a suitable support as shown in Figure 1. The movable chuck 15 is then forced into engagement with the drill so that the latter is clamped between the two chucks. The rod 20 is inserted into one of the hollow ears 19 and the head 8 is turned thereby. This turning movement, of course, imparts a turning movement to the drill which is clamped to the head and at the same time the engagement of the screw thread 6 of the screw 7 with the screw threads 5 of the base will cause the screw 7 and drill to move upwardly. If found necessary the base may be held in position by means of the rod 4 and handle 2.

If it is desired to give a direct pull without any turning movement, the chuck 15 is loosened so that the chucks do not engage the drill member. A wrench B is clamped to the drill stem A just above the collar 21 and held to prevent any rotation of the drill A. The head is then turned by means of the rod 20 as previously, and this turning movement will impart a longitudinal movement to the screw 7 and the head 8 but will

not impart any turning movement to the drill A. It may be noted that the device may also be used as a lifting jack by placing it so that the object to be lifted rests upon the collar 21 and turning the head 8 in the usual manner.

It will be evident that the invention provides a simple and efficient mechanism adapted to clamp any rod, drill or hollow pipe without the necessity of any special provisions or unusual construction of the drill or pipe. It is also apparent that merely a longitudinal movement may be imparted to the drill or pipe or a combined longitudinal and twisting movement may be obtained by a simple adjustment of the mechanism. The precise form and proportions of the various parts may be widely varied and details of construction may be changed without in any way departing from the spirit of the invention, which is to be regarded as limited only by the scope of the appended claims.

I claim as my invention:

- 25 1. A jack comprising a hollow base member, a hollow screw member screw-threaded in said base and having a head, and relatively adjustable chuck jaws carried by said head within the same and in position to engage an article passing through the hollow screw member.
- 30 2. A jack comprising a hollow base member, a hollow screw member screw-threaded in said base and having a head, a chuck member rigidly held in said head, a cooperating chuck member adjustably mounted in said head, and means for adjusting the latter chuck member to clamp an article passing through the hollow head between the chucks.

3. A jack comprising a hollow base member, a hollow screw member screw-threaded in said base and having a head, a chuck member rigidly held in said head, a cooperating chuck member adjustably mounted in said head, means for adjusting the latter chuck member to clamp on article passing through the hollow head between the chucks, and means for turning said head to both rotate said article and move it longitudinally.

4. A jack comprising a hollow base member, a hollow screw member screw-threaded in said base and having a head, relatively adjustable chuck jaws carried by said head in position to engage an article passing through the hollow screw member, a collar 55 rotatably mounted on said head and means for turning said head.

5. A jack comprising a hollow base member, a hollow screw member screw-threaded in said base and having a head, relatively 60 adjustable chuck jaws carried by said head within the same and in position to engage an article passing through the hollow screw member, screw means for adjusting one of said chuck members, and means for turning 65 the head.

6. A jack comprising a hollow base member, a hollow internally screw-threaded bushing held against rotation on said base, a hollow screw member screw threaded into 70 said bushing and having a head, relatively adjustable chuck jaws carried by said head within the same, and means for turning said head.

In testimony whereof, I have hereunto 75 subscribed my name.

GABRIELLO OSANNI.
